UNITED STATES PATENT OFFICE.

CHARLES J. NASH, OF CHICAGO, ILLINOIS, ASSIGNOR TO UNIVERSAL DRAFT GEAR ATTACHMENT CO., A CORPORATION OF ILLINOIS.

DRAFT-ARM.

1,265,991.

Specification of Letters Patent. Patented June 11, 1918.

Application filed August 10, 1917. Serial No. 185,455.

To all whom it may concern:

Be it known that I, CHARLES J. NASH, a citizen of the United States, and resident of Chicago, county of Cook, and State of Illinois, have invented certain new and useful Improvements in Draft-Arms, of which the following is a specification, and which are illustrated in the accompanying drawings, forming a part thereof.

18 The invention relates to draft castings for railway cars, and is shown as embodied in a draft-arm extending from the end sill of the car to and beyond the bolster, though it is equally applicable to draft plates which are 15 of shorter formation.

The object of the invention is to provide for an improved mounting of the carry iron for supporting the draw-bar and the supporting strap upon which the draft gear 20 rides, or for either of these devices.

A preferred embodiment of the invention is hereinafter described and is illustrated in the accompanying drawings, in which—

Figure 1 is a detail longitudinal sectional 25 view of the underframing of a car, showing the outer face of one of the sills, and the draft-arm associated therewith, in elevation;

Fig. 2 is a detail plan section on the line 2—2 of Fig. 1, some of the parts being 30 omitted;

Fig. 3 is a detail sectional view on the line 3—3 of Fig. 1;

Fig. 4 is a detail sectional view on the line 4—4 of Fig. 1; and

Fig. 5 is a detail in perspective of a portion of the draft-arm.

A pair of center sills, shown as of wood, are represented at 10, 11, and the end sill of the car at 12. The usual buffing plate 13 40 may be of any desired form. The coupler is shown at 14, and its extension or yoke at 15. The coupler and its extension are suitably united, as by means of the key 16. All of these parts, as shown, are without novelty 45 and are not necessarily of the type illustrated.

The draft casting 17 is shown as having the form of a draft arm extending from below the buffing plate 13 to and abutting 50 against the bolster 18, and having an extension 19 which arches over the bolster and is secured to the center sill, as 11, by means of bolts. This arm is provided with a draft shoulder 20 and a buffing shoulder 21 for 55 cooperating with the draft gear which will

be inclosed within the yoke 15. The arm is shown as designed for use in connection with the well-known Cardwell type of draft gear, and for that reason is provided with an aperture 22 for the accommodation of the 60 transverse spring-carrying rod forming a part thereof.

The arm is provided with the usual lateral flange 23 along its lower margin. At the forward end of the arm there is formed an 65 aperture 24 immediately above the flange 23 for the reception of the carry iron 25 on which the shank of the coupler 14 rests, and in line with the center of this aperture the flange 23 is perforated, as shown at 26, to 70 accommodate a bolt 27 for securing the carry iron in place. Preferably the carry iron 25 is provided, at one end with a depending gib 28 for engaging the margin of the flange 23, though if desired it may be 75 secured at both ends by bolts, as 27.

Formed upon the outer surface of the arm 17 immediately above the aperture 24, and in line with the bolt-hole 26, is an outstanding beveled boss 29, with which the 80 head of the bolt 27 engages and by which it is deflected outwardly, putting the carry iron 25 under tension and securely locking it in place. For the purpose of adding strength to the casting a bead 30 may be 85 formed on the outer face of the arm extending from the boss 29 in each direction and bounding the top and end margins of the slot 24.

The supporting strap 31 for carrying the 90 gear is or may be of the same configuration as the carry iron 25, though usually somewhat wider, and the draft arm is similarly apertured for its accommodation, the aperture being located immediately above the 95 flange 23 and the outer surface of the arm being provided with a beveled boss 32 above it and in line with the bolt-hole for receiving the retaining bolt 33. The supporting strap may also be provided with a depending 100 gib 34 at one end for engaging the margin of the flange 23, or it may be secured at both ends by means of bolts.

The described construction provides a 105 strong support for the carry iron and supporting strap without weakening the draft-arm. It secures these parts firmly in position, avoiding movement and consequent wear, and in such manner as to put them under tension and thus cause them to resist 110

the tendency to a spreading of the draft plates under the stresses of draft and buffing. Ordinarily the bead 30 will not be required and is not essential to the action of the boss 29.

The novel features described are not dependent upon the general character of the draft casting. Various details of the invention may be varied from the construction 10 illustrated without departing from its scope. For example, while the flange 23 is shown as at the extreme lower edge of the casting, it is important only that this flange and the apertures for receiving the carry iron 15 and supporting plates shall be in proper relation to the coupler and draft gear.

I claim as my invention—

1. A draft casting comprising a body portion having a lateral flange adjacent to its 20 lower margin, an aperture adjacent to and above the flange for receiving a bar for supporting a portion of the draft rigging of a car, and a beveled boss at the upper margin of the aperture.

2. In combination, a pair of draft cast-

ings each having a lateral flange adjacent to its lower margin, an aperture above and adjacent to the flange and one of said castings having a beveled boss at the upper margin of the aperture, and a bar passing 30 through the aperture of the two arms and having a gib at one end overhanging the flange of one casting and being bolted to the flange of the other casting, the head of the attaching bolt bearing upon the boss. 35

3. In combination, a pair of draft castings each having a lateral flange adjacent to its lower margin and apertures above and adjacent to the flange, one of such arms having a beveled boss at the upper margins of its 40 apertures, a carry iron and gear-supporting plate extending through corresponding apertures of the two castings, such iron and plate each having a gib at one end engaging the margin of one of the castings and being bolted to the flange of the other casting, the heads of the attaching bolts bearing against the boss associated with the casting aperture. 45

CHARLES J. NASH.
